CLAIM

The ornamental design for a dispensing carton as shown and described.

DESCRIPTION

FIG. 1 is a perspective view of a dispensing carton showing our new design.

FIG. 2 is a left elevation view of the dispensing carton of FIG. 1, the right elevation view is a mirror image.

FIG. 3 is a front elevation view of the dispensing carton of FIG. 1, the rear elevation view is a mirror image.

FIG. 4 is a top plan view of the dispensing carton of FIG. 1.

FIG. 5 is a bottom plan view of the dispensing carton of FIG. 1; and,

FIG. 6 is a plan view of the dispensing carton of FIG. 1 shown in an unfolded configuration.

All evenly-spaced broken lines are for environmental purposes only and do not form part of the claimed design.

1 Claim, 6 Drawing Sheets

US D1,088,865 S
